Attorneys.

UNITED STATES PATENT OFFICE.

NINIAN J. TURNER, OF LINCOLN, NEBRASKA.

LABEL HOLDER FOR RESERVE-STOCK RECORDS.

Application filed March 10, 1921. Serial No. 451,397.

To all whom it may concern:

Be it known that I, NINIAN J. TURNER, a citizen of the United States, residing at Lincoln, in the county of Lancaster, State 5 of Nebraska, have invented certain new and useful Improvements in Label Holders for Reserve-Stock Records; and I do hereby declare the following to be a full, clear, and exact description of the invention, such as 10 will enable others skilled in the art to which it appertains to make and use the same.

This invention relates to new and useful improvements in recording and registering devices and particularly to devices for recording or registering mercantile reserve stocks.

The principal object of the invention is to provide a device by means of which a record can be accurately kept of the amounts of 20 different articles of merchandise carried in stock and which will show the merchant, at a glance what articles are in stock and what articles are out of stock.

Another object is to provide a novel and 25 improved means for mounting the name of the article of merchandise on the recording device.

Other objects and advantages will be apparent from the following description when 30 taken in connection with the accompanying drawing.

In the drawing:

Figure 1 is an elevation of the device, showing what articles are in stock and what 35 articles are out of stock.

Figure 2 is an enlarged vertical longitudinal sectional view through the device, on the line 2—2 of Figure 1, which passes through certain of the covering slides, and 40 the name holder.

Figure 3 is a plan view of the blank from which the body of the device is formed.

Referring particularly to the accompanying drawing 10 represents a sheet metal 45 plate which forms the base or body of the device. Formed transversely through the sheet 10, in parallel pairs, are the slots 11, and printed, or otherwise formed on the portion of the sheet, between each pair of 50 slots, and adjacent one end thereof, is a number, letter, or other symbol, representing the character, size, or number of the merchandise. A short strip of metal 12, of a width approximately one-half the length 55 of the slots, has its ends disposed through a pair of slots, and said ends bent toward each

other to lie against the rear face of the metal sheet, as shown in the sectional view Figure 2. The strip, however, embraces the portion of the sheet between the slots, sufficiently firm to prevent accidental displacement thereof, but loosely enough to readily permit the strip to be slipped from one end of the slots to the other, for the purpose of covering or uncovering the symbol on such 65 portion of the sheet.

The particular use of the device illustrated is for dealers in men's attire, and particularly for recording the state or condition of the reserve stock with respect to 70 men's collars. On the portions of the sheet, between the pairs of slots, are printed the sizes of the collars, and when the sizes are in stock the strip 12 is moved to one end of the slots to expose the size number, but 75 when the reserve stock is exhausted, the strip is slipped to the other end and the number thus hidden. This indicates that the reserve stock of that particular size of collar is exhausted.

In the center of the upper end of the sheet 10 are formed the vertically aligned pairs of short slots 13. A long narrow strip of metal 14 has its ends passed through the upper slots 13 so as to extend transversely of 80 the sheet, and its ends bent transversely toward each other against the back of the sheet. A second long narrow strip of metal 15 has its ends disposed through the lower slots 13, and treated back of the sheet in the 85 same manner as the ends of the strip 14. The intermediate portion of the lower edge of the second strip 15 is formed with a tab 16 which is turned inwardly toward the sheet 10 and upwardly. A card or plate, 90 on which is inscribed the name of the merchandise (in the present illustration the name of the collar), is passed down between the sheet 10 and the strips 14 and 15, with its lower edge resting on the bight of the up- 95 turned tab 16. This tab insures that the card will not slip down, while the ends of the strips which pass through the slots 13 hold the card against longitudinal movement.

It will, of course, be understood that the name card at the top might have formed thereon the name of any particular article of merchandise, and the numbers on the sheet, between the slots 11 be any other symbols 100 representing the character, or quantities of the articles in reserve stock. The use of 110

the device in connection with collars serves merely as a concrete instance.

Figure 3 shows the blank from which base member 10 is formed. It will be noted that 5 the corners are cut off obliquely, as shown at 17, and that the blank is adapted to be folded on the lines 18, at the ends, and on the lines 19, at the sides, with the result that this double thickness of metal around 10 the marginal edges serves to brace and strengthen the sheet.

In each corner of the sheet 10 is formed an opening 10' for reception of means for securing the sheet to the receptacle or case 15 containing the articles printed on said sheet.

What is claimed is:

In a device of the class described, the combination with a base plate having a plu-

rality of slots, a pair of strips of bendable material having their ends disposed through 20 certain of the slots and disposed flatly against the rear face of the base plate and with the portions between the slots spaced from the front face of the plate, one of said strips being formed with a tab which is 25 extended inwardly through another of the slots, the strips, between the slots, and the tab, being arranged to support a label, card, or the like, with the legend of the label visible between the strips.

In testimony whereof, I affix my signature, in the presence of two witnesses.

NINIAN J. TURNER.
